Des. 180,708
Patented July 30, 1957

180,708

PORTABLE POWER OPERATED SABER SAW

John P. Bruck, Toledo, Ohio

Application December 28, 1956, Serial No. 44,345

Term of patent 14 years

(Cl. D93—3)

Fig. 1

Fig. 2

Fig. 3Fig. 4Fig. 5

Figure 1 is a top plan view of a portable power operated saber saw embodying my new design.

Figure 2 is a side elevational view looking upwardly in Figure 1.

Figure 3 is a side elevational view looking downwardly in Figure 1.

Figure 4 is an end elevational view, with a portion of the handle knob broken away, looking to the right, Figure 3.

Figure 5 is an end elevational view looking to the left, Figure 3.

I claim:

The ornamental design for a portable power operated saber saw, as shown.
